CLAIM

The ornamental design for an insert with provision for power outlets for a ready-to-assembly furniture grommet, as shown and described.

DESCRIPTION

FIG. 1 is a front elevational view showing my design;

FIG. 2 is a right side elevational view of FIG. 1, the left side view being a mirror image thereof;

FIG. 3 is a top view of FIG. 1;

FIG. 4 is a bottom view of FIG. 1;

FIG. 5 is a perspective view of FIG. 1;

FIG. 6 is a front elevational view showing a second embodiment of my design;

FIG. 7 is a right side elevational view of FIG. 6, the left side view being a mirror image thereof;

FIG. 8 is a top view of FIG. 6;

FIG. 9 is a bottom view of FIG. 6; and,

FIG. 10 is a perspective view of FIG. 6.
